United States Patent Office

Des. 176,149
Patented Nov. 22, 1955

176,149

ATOMIZER

Henri Gerard Edmond Lemaire, Limoges, France
Application November 1, 1954, Serial No. 32,893

Term of patent 14 years

(Cl. D83—1)

FIG. 1

FIG. 2

FIG. 3

FIG. 4

Fig. 1 is a perspective view of an atomizer, showing my new design;

Fig. 2 is a front elevational view;

Fig. 3 is a rear elevational view; and

Fig. 4 is a top plan view.

The dominant features of my design reside in the portions shown in full lines.

I claim:

The ornamental design for an atomizer, as shown and described.
